WRAPPER TUBE FORMING MACHINE

Vern R. Luce, Los Angeles, Calif.

Application April 12, 1938, Serial No. 201,544

12 Claims. (Cl. 93—18)

My invention relates to a machine for producing tubular wrappers from a strip or web of thin, flexible material, such as Cellophane, waxed paper, or the like, and the principal object of my invention is to provide a machine of the character referred to that is entirely automatic in its functions, and which very rapidly and economically shapes a strip of flexible material into tubular form, twists the forward end of the tube so as to close the same, and then severs the tube at a point a pre-determined distance to the rear of the twisted forward end so as to produce tubular wrappers, each having one end closed, and said wrappers being ready to be filled, and the open end closed by manual twisting operation.

The tubular wrappers produced by my improved machine, may be used for packaging various products; for instance, candy and various confections; nut meats; cigars or cigarettes; in fact, any product that may be packed and more advantageously displayed for sale, in moisture and dust proof, transparent containers.

Further objects of my invention are to generally improve upon and simplify the construction of the existing forms of wrapper tube forming machines; to provide a machine wherein a reciprocating plunger is utilized for imparting forward movement to the tubular wrapper after the same has been given its tubular form by a fixed shaper. Further, to provide plunger driving mechanism that will move said plunger forwardly with a slow motion, and rearwardly with a much faster motion, and to provide simple means whereby the reciprocating stroke of the plunger may be easily and conveniently adjusted, so as to vary the length of the wrapper tubes produced by the machine.

Further objects of my invention, are to provide simple and efficient means for engaging and twisting the open forward end of the tubular wrapper; and also to provide simple and positively acting means for severing the tubular wrappers into proper and uniform lengths.

With the foregoing and other objects in view, my invention consists in certain novel features of construction and arrangement of parts that will be hereinafter more fully described and claimed and illustrated in the accompanying drawings in which:

Fig. 1 is a top plan view of a wrapper tube forming machine, constructed in accordance with my invention.

Fig. 2 is a side elevational view of the machine with a portion of the table shown in section.

Fig. 3 is an enlarged vertical section taken on the line 3—3 of Fig. 1.

Fig. 4 is an enlarged cross section taken approximately on the line 4—4 of Fig. 1.

Fig. 5 is an enlarged cross sectional view taken approximately on the line 5—5 of Fig. 1.

Fig. 6 is a detail elevational view, partly in section, and showing the jaws that grip the tubular wrapper to the plunger.

Fig. 7 is an enlarged cross sectional view taken on the line 7—7 of Fig. 1.

Fig. 8 is an enlarged cross sectional view taken on the line 8—8 of Fig. 1.

Fig. 9 is an enlarged cross sectional view taken on the line 9—9 of Fig. 1.

Fig. 10 is a detail elevational view, partly in section, of the means employed for twisting the forward end of the wrapper tube.

Fig. 11 is a cross section taken approximately on the line 11—11 of Fig. 10.

Fig. 12 is a fragmentary sectional view similar to Fig. 11 and showing one of the twisting fingers engaged by a revolving cam.

Fig. 13 is an enlarged vertical section taken on the line 13—13 of Fig. 2.

Fig. 14 is a perspective view of one of the wrapper tubes as formed by my improved machine.

Referring by numerals to the accompanying drawings which illustrate a practical embodiment of my invention, 10 designates a table supported by legs 11, and secured to and projecting rearwardly from said table is a pair of spaced parallel rails 12. The trunnions 13 of a shaft 14 are journaled in the outer ends of the rails 12, and said shaft carries the spool 15 upon which is wound a strip or web 16 of thin, flexible material; for instance, Cellophane, waxed paper, or the like, from which the wrapper tubes are formed.

The free end of a flat spring 17 that is adjustably mounted on one of the rails 12, bears on one of the trunnions 13, so as to prevent the spool 15 from rotating too freely during operation of the machine.

Depending from the rails 12 are hangers 18, in which are arranged for vertical sliding movement, trunnions on the ends of a small roller 19, beneath which passes the web 16 of the wrapping material. Depending from the lower ends of these hangers 18, are rods 20 on which are adjustably mounted collars 21, and secured to said collars are the lower ends of retractile springs 22, the upper ends of which are secured to the trunnions on the ends of roller 19.

This roller takes up the slack in the web 16.

- between the spool 15 and the wrapper tube forming means hereinafter described, and the springs 22 yieldingly resist the upward movement of roller 19.
- 5   Journaled on the rails 12 immediately in front of the hangers 18, are the ends of a roller 23 over which the web 16 passes in its travel toward the tube forming member, and which latter is suitably supported upon the rails 12 and upon 10 the adjacent end of table 10.
- The shaping and forming member 24, which is illustrated in plan view in Fig. 1 and in cross section in Figs. 7, 8, and 9, is formed from thin sheet metal and comprises a channel-shaped bottom portion 25, the sides of which are folded over into position immediately above and spaced apart from the sides of the body of said member 25, as designated by 26.
- 15   The end of the former immediately adjacent to the roller 23 is flat and occupies a horizontal position as illustrated in Fig. 7, so that the web of material 16 enters the former between the flat bottom portion 25 and the flat overlying portions 26 in corresponding flat condition. The side 20 edges of the metal in the bottom 25 and overlying portions 26 are curved upwardly and inwardly, as designated by 27, and these curved portions gradually approach each other toward the end of the former that rests on table 10, with the result that the intermediate portion of the former is substantially channel-shaped in cross section as illustrated in Fig. 8, and the forward portion of said former is substantially tubular in shape as illustrated in Fig. 9, with a longitudinally disposed 25 slot or opening 27 between the upper edges of the inwardly folded side portions, and which slot is for the accommodation of the downwardly turned end of an arm 28 that is connected to the rear end of a reciprocating plunger 29.
- 20   This plunger is mounted for longitudinal reciprocating movement in bearings 30 that project upwardly from table 10, and a rod 31 connects the rear end of the arm 28 with the rear end of said plunger.
- 25   This plunger is mounted for longitudinal reciprocating movement in bearings 30 that project upwardly from table 10, and a rod 31 connects the rear end of the arm 28 with the rear end of said plunger.
- 30   The forward end of arm 28 is rigidly secured to a carriage 32 that is mounted for reciprocating movement on rails 33, the ends of which are supported by brackets 34 that project upwardly from table 10.
- 35   Pivoted connected to the side of carriage 32, is the upper end of an arm 35 that extends downwardly through a slot 36 in table 10, and the lower end of this arm is pivotally connected to one end of a rod 37, the opposite end of which is pivotally connected to a bracket 38 that is secured to one of the legs 11.
- 40   Secured to and depending from the rear portion of table 10, is a bracket 39 in which is journaled one end of a horizontally disposed shaft 40 that extends lengthwise beneath the table 10 with its forward portion journaled in a bearing 41. This shaft 40 extends a short distance beyond the bearing 41, and mounted on the end of said shaft is a hand wheel 42 that may be engaged, in the 45 event that it becomes necessary to manually rotate shaft 40.
- 45   Mounted on a platform 43 that is secured to the rear legs 11, is an electric motor 44, having a conventional driving connection with a pulley 45 that is journaled in the lower portion of bracket 39. Mounted on the shaft that carries the pulley 45, is a worm 46 that engages a worm wheel 47, the latter being fixed on the rear portion of shaft 40. Thus the motor 44 imparts rotary motion 50 to shaft 40.
- 55   Pivoted mounted on a bracket 48, on the under side of table 10, is the upper end of a depending lever 49, the lower portion of which is slotted lengthwise as designated by 50, and mounted for rotation on said lever and extending 5 lengthwise of slot 50, is a threaded rod 51. This threaded rod 51 passes through a block 52, so that the latter may be adjusted lengthwise of lever 49, and screw-seated in said block is one end of a rod 53, the opposite end of which is screw-seated 10 in a block 54, and the latter being adjustably mounted on the intermediate portion of arm 35.
- 60   The construction just described permits block 54 to be adjusted vertically upon arm 35, and block 52 to be adjusted vertically on lever 49, and further adjustment of the blocks 52 and 54 toward and away from each other, and which adjustment provides for the very accurate regulating of the reciprocatory movement imparted to plunger 29.
- 65   Mounted on shaft 40 below bracket 48, is a grooved cam 55, and secured to the upper portion of lever 49 and projecting into the groove of said cam, is a pin or bolt that carries a roller 56. Thus cam 55 imparts swinging movement to lever 49, and through rod 53 arm 35 is swung backward and forward to impart reciprocatory movement to carriage 32.
- 70   The means for twisting the forward end of the tubular wrapper and for cutting the formed wrapping material into sections of proper length, is located on the forward end of the table 10, and these particular mechanisms are illustrated in Figs. 3 to 6 inclusive, and in Figs. 10, 11, and 12.
- 75   Formed in the forward portion of table 10, is an opening 57, and secured on the table above said opening is a substantially circular frame 58 that serves as a support for the twisting head assembly. Mounted to rotate freely in frame 58 is a ring 59 that is concentric with the axis of plunger 29, and formed on the exterior of this ring is a ring-gear 60. Mounted to rotate freely on ring 59 is a ring-gear 61, the diameter of which is slightly greater than that of the ring-gear 60. Secured to the side face of ring-gear 61 at diametrically opposite points are arcuate cams 62 that are effective in imparting closing movement to the twisting fingers.
- 80   These fingers, of which there are two, comprise body portions 63, the outer ends thereof being pivoted at 64 to the inner face of ring 59, and formed integral with and projecting outwardly through openings 65 in ring 59, are curved lugs 66 that are directly in the path of travel of the cams 62. Secured to the rear side of each finger 63 is one end of a flat spring 67, the free end of which carries a pin 68 that projects through an opening 69 in the free end of the finger, and mounted on the end of the pin 68, opposite the end that is secured to the spring, is a wrapper 60 engaging button 70, having a corrugated face.
- 85   When the fingers 63 are swung toward each other, the corrugated faces of the buttons 70 engage the end of the tubular wrapper, and after closing said wrapper the engaged end is twisted, 65 as will be hereinafter more fully described.
- 90   Secured to the intermediate portion of each finger 63 is one end of a retractile coil spring 71, the other end of said spring being connected to ring 59, and in order to limit the swinging motion of the fingers away from each other, stops 72 are secured to the inner face of ring 59 and project inwardly toward the twisting fingers.
- 95   Mounted on top of table 10 directly in front of the frame 58, is a bracket 73 provided with an 75

opening 74, that is in alignment with the opening in frame 58.

Mounted on top of this bracket is a small bracket 75, in which is journaled a pair of spaced shafts 76. Secured to and depending from each shaft is a shear blade 77, and the lower portions of said blades are adapted to pass one another so as to sever the tubular wrapper that projects through the twisting head beyond the forward end of the plunger. Secured to one of these shafts 76 is a short arm 78, the inner end thereof being provided with teeth 79 that engage the teeth of a pinion 80 that is mounted on the other shaft. Thus, as the shaft 76 that carries the arm 78 swings on its axis, pinion 80 will be correspondingly rotated to rotate the shaft upon which it is mounted, so that the shear blades 77 will move toward each other to sever the tubular wrapper that extends between said blades.

Pivoted connected to the outer portion of the arm 78, is the upper end of an arm 81 that extends downwardly through the opening 57 in table 10, and the lower end of this arm is bifurcated by 82 for the accommodation of shaft 40.

Secured on shaft 40 adjacent the lower end of this arm, is a cam 83, and projecting from the lower portion of arm 81 into the groove in said cam is a pin or roller 84. The groove in this cam 83 has an indented portion 85 that projects inwardly toward the shaft 40, so that as the cam rotates, the passage of the pin or roller 84 through the indented portion of the groove will draw arm downwardly, so as to swing the shear blades 77 toward each other.

The upper end of an inclined chute 86 is positioned in the opening 57, directly below the brackets 75 and 78, and said chute receives the severed wrapper tubes and delivers the same into a receptacle positioned beneath the lower end of said chute.

The means for gripping the forward portion of the tubular wrapper and holding the same against rearward movement as the plunger 29 moves rearward, comprises a pair of vertically disposed fingers 87 pivoted at 88 to the upper portion of frame 58, and portions of the adjacent faces of the upper ends of these fingers have toothed engagement with each other, as designated by 89.

Projecting upwardly from the upper end of one finger is a lug 90, in which is adjustably seated one end of a rod 91, the outer end thereof being adjustably mounted on the upper end of a vertically disposed lever 92. This lever which extends downward through the opening 57 in the table is fulcrumed at 93 to the frame 58, and the lower end of said lever carries a roller 94. This roller is in position to be engaged by a cam 95 that is carried by shaft 40, and as the result of such engagement, lever 92 is swung on its fulcrum and through rod 91, one of the fingers 88 is swung on its axis and through the toothed engagement between said fingers, the other finger 87 is correspondingly swung so that the two fingers move simultaneously toward and away from each other.

The lower ends of the fingers 87 carry short cylindrical members 96 of rubber that are positioned on opposite sides of plunger 29, so as to press the tubular wrapper against said plunger.

Pivoted connected to the intermediate portion of one of said fingers 87, is one end of a rod 97, the opposite end of which passes through the opposite finger, and mounted on the project-

ing end of said rod is an expansive coil spring 98, the tension of which may be regulated by a nut 99 that is screw-seated on the rod. Thus, the pressure of the rubber covered ends of the fingers 87 may be accurately adjusted.

The means for transmitting rotary motion from the shaft 40 to the ring 59 and the ring 61 that carries the cams 62 include a gear wheel 100 that is mounted on shaft 40, and said gear wheel engages a pinion 101 that is carried by a shaft 102, and the latter being journaled in a bearing that is formed on a bracket 103. This bracket is secured to and depends from the table 10 immediately to the rear of opening 57, and secured on shaft 102 is a gear wheel 104. This gear wheel 104 engages a pinion 105 that is carried by a shaft 106, the latter being journaled in a bearing on bracket 103, and secured to said shaft 106 is a gear wheel 107. This last mentioned gear wheel meshes with a pinion 108 carried by a shaft 109 that is journaled in a bearing on bracket 103, and secured to said shaft 109 is a gear wheel 110 that meshes with the teeth of ring-gear 60 on ring 59.

A gear wheel 111 is carried by shaft 109 immediately adjacent the gear wheel 110, and the diameter of said gear wheel 111 is slightly less than that of gear wheel 110. This gear wheel 111 meshes with the teeth of ring-gear 61 that carries the twisting finger actuating cams 62.

The gearing just described is for the purpose of imparting rotary motion of the proper speed from the motor driven shaft 40 to the ring 59 and to the twisting finger closing means comprising the ring-gear 61 and cams 62.

Briefly, the operations incident to the formation of wrapper tubes, each having one end closed by being twisted, are as follows:

While the twisting fingers 63 and the fingers 87 carrying the wrapper gripping members 96 are open or spread apart, the plunger 29 is moved forward against the closed end of the tubular wrapper, which end was closed by the preceding twisting action of fingers 63, and the tubular wrapper will be moved forward a predetermined distance through frame 58, during which forward movement the forward portion of the plunger carrying the tubular wrapper moves between the blades 77 which are spread apart.

During this forward movement, a corresponding portion of the web 16 of the thin material used in producing the wrappers will be unwound from spool 15 and will be drawn through the forming member 24 which gradually gives the strip of material tubular shape, and in such form it passes on to the plunger 29.

At the end of the forward travel of the plunger, fingers 87 swing toward each other so as to bring the elastic members 96 into engagement with the tubular wrapper on the plunger, and thus said wrapper is held against rearward movement with the plunger.

During the rearward movement of the plunger, or as soon as the forward end thereof passes rearwardly from the blades 77, the latter are actuated to cut off that portion of the tubular wrapper in front of said blades, which portion has its forward end closed, and the wrapper on being severed drops into and passes through chute 86.

Immediately following this severing operation, the twisting fingers 63 close so that the buttons 70 on the ends thereof engage and close the forward end of the tubular wrapper, and the twisting

5 fingers are now revolved approximately two complete revolutions to close the same, during which time the elastic members 96 on fingers 87 are in engagement with the tubular wrapper to hold the same against rotation on the plunger while the twisting fingers are functioning.

10 As the plunger starts forward on its subsequent movement through the tubular wrapper, so as to engage the twisted forward end thereof and feed the wrapper forwardly through the machine, the twisting fingers open or spread apart and simultaneously the fingers 87 carrying the pressure members 96 open or spread apart, so that the tubular wrapper is free to be moved forward by 15 the forwardly moving plunger.

15 In the operation of the plunger 29, motor 44 drives pulley 45 and through worm 46 and worm-wheel 47 continuous rotary motion is imparted to shaft 40 and the parts carried thereby.

20 As cam 55 rotates, lever 49 will be swung backward and forward, thereby imparting swinging movement to arm 35, and as the latter is actuated, carriage 32 will be reciprocated to impart corresponding movement through rod 31 and arm 25 28 to plunger 29.

25 The adjustable connections between rod 53, lever 50 and swinging arm 35, enable the stroke or length of travel of the plunger to be very accurately regulated.

30 Fingers 87 carrying the rubber covered ends 96 that press against the tubular wrapper on the plunger to hold the same against rearward and rotary movement, are actuated in proper time relation to the movements of the other parts of the machine by the engagement of cam 95 with roller 94, which swings lever 92 on its fulcrum and through rod 91 imparts swinging movement to the finger 87 to which said rod is connected.

35 The degree of pressure of the rubber covered ends of the fingers against the tubular wrapper and plunger, may be adjusted by manipulation of nut 99 on the threaded end of rod 97.

40 The blades 77 are swung together in proper time relation to the movement of the tubular wrapper through the machine, to cut off the forward portion thereof by the action of the cam 83 on roller 84 to move arm 81 lengthwise and thereby impart rocking motion to the arm 78 and the two blades moving in unison, due to the engagement 45 of the teeth 79 with pinion 80.

45 Ring 59 carrying the twisting fingers and the ring 61 that swings the ends of said twisting fingers toward each other to engage the end of the wrapper tube, are actuated in proper time relation to the movements of the tubular wrapper through the machine by the train of reduction gearing comprising the gear wheel 100 carried by shaft 40, pinion 101, gear wheel 104, pinion 105, gear wheel 107, pinion 108, and gear wheels 110 50 and 111, which mesh respectively with ring-gears 60 and 61.

55 Gear wheel 110 drives ring 59 and the twisting fingers carried by said ring make approximately two revolutions while the buttons 70 are in engagement with the end of the wrapper tube, thus producing two complete twists of the material.

60 Gear wheel 111 drives ring-gear 61 and the latter carries the cams 62, which in operation engage the lugs 66 on the outer ends of the fingers 70 63, so as to close said fingers or move the same toward each other. Ring-gear 61 is slightly larger in diameter than ring-gear 60 and gear wheel 111 that drives ring-gear 61 is slightly less in diameter than gear wheel 110, with the result 75 that the ring-gear 61 that carries the twisting

finger closing cams 62, operates at slightly less speed than the twisting finger carrying ring 59 that is driven by gear wheel 110.

5 The forward end of the shaft 40 is provided with the hand wheel 42, so as to enable the various operating parts of the machine to be moved into different positions to facilitate inspection, repair, adjustments, and also for the purpose of permitting the web of material 16 to be "threaded" through the machine at the beginning of the 10 wrapper tube forming operations.

15 Projecting forwardly a short distance from the forward one of the bearings 30, is a short tube 30a through which the tubular wrapper passes as it is moved forward by the reciprocating plunger 15 and the sides of this tube are cut away to form openings 30b that permit the elastic members 96 carried by the fingers 87 to engage the tubular wrapper at diametrically opposite points when the lower portions of the fingers are moved toward each other.

20 Thus while the rubber covered portions of the fingers are in engagement with the tube, the latter is held in proper position immediately to the rear and in front of the pressure fingers by 25 the circumferential portions of the tube 30a in front and to the rear of the openings 30 (see Figs. 3 and 6).

25 One of the particular advantages of my improved wrapper tube forming machine, is that 30 the wrappers of thin, flexible material, such as Cellophane, waxed paper or the like, are produced without the use of an adhesive and without the requirement for heat treatment in the sealing of the tubes for the twisting of the ends 35 of the tubes, one by the machine and the other by hand, effectively closes the wrapper and protects the contents thereof.

35 Thus it will be seen that I have provided a 40 wrapper tube forming machine that is relatively simple in construction, inexpensive of manufacture, and very effective in performing the functions for which it is intended.

45 It will be understood that minor changes in the size, form and construction of the various 45 parts of my improved wrapper tube forming machine, may be made and substituted for those herein shown and described, without departing from the spirit of my invention, the scope of which is set forth in the appended claims.

50 I claim as my invention:

55 1. In a wrapper tube forming machine, a table, a plunger mounted for reciprocatory movement on said table, means for delivering wrapping material in tubular form to said plunger, means mounted on the table for twisting the end of the tubular wrapper in advance of the forward end of said plunger, means for severing the wrapper tube at a point to the rear of its twisted forward end and means for imparting reciprocatory 60 movement to said plunger.

65 2. In a wrapper tube forming machine, a table, a plunger mounted for reciprocatory movement on said table, means for delivering wrapping material in tubular form to said plunger, means mounted on the table for twisting the end of the tubular wrapper in advance of the forward end of said plunger, means for severing the wrapper tube at a point to the rear of its twisted forward end and means for operating said reciprocating plunger, said twisting means and said severing means, in proper time relation to the movements of said plunger and the wrapper tube carried thereby.

70 3. In a wrapper tube forming machine, a table,

- a plunger mounted for reciprocatory movement on said table, means for delivering wrapping material in tubular form to said plunger, means mounted on the table for twisting the end of the tubular wrapper in advance of the forward end of said plunger, means for severing the wrapper tube at a point to the rear of its twisted forward end, means for imparting reciprocatory movement to said plunger and means for operating said wrapper tube twisting means and severing means in proper time relation to the movements of said reciprocating plunger.
4. In a wrapper tube forming machine, a table, a plunger mounted for reciprocatory movement on said table, means for delivering wrapping material in tubular form to said plunger, means on the table in advance of said plunger for twisting the end of the wrapper tube carried thereby and means for engaging the wrapper tube on the plunger and holding the same against rearward movement with the plunger and against rotary movement during operation of the twisting means.
5. A wrapper tube forming machine as set forth in claim 4, with wrapper tube severing means mounted on the table in front of said twisting means.
6. In a wrapper tube forming machine, a table, means for supporting a roll of wrapper tube forming material on the rear portion of said table, means on the rear portion of the table for giving tubular shape to the web of wrapper material as it unwinds from said roll, a plunger mounted for reciprocatory movement on the table, which plunger receives the wrapping material after the same has been given tubular form, means for imparting reciprocatory movement to said plunger, pressure fingers mounted for operation to the sides of the forward portion of the means that gives tubular shape to the web of wrapper material, means for moving said pressure fingers away from each other and means for moving said pressure fingers toward each other to press the wrapper material against the plunger.
7. A wrapper tube forming machine as set forth in claim 6 and with means on the table in advance of said reciprocating plunger for twisting and closing the forward end of the wrapper tube.
8. A wrapper tube forming machine as set forth in claim 6, with means on the table in advance of the plunger for twisting and closing the forward end of the tubular wrapper and means on the table in front of said twisting means for severing the forward portion of said wrapper tube 10 after its forward end has been twisted and closed.
9. A wrapper tube forming machine as set forth in claim 6, with means on the table in advance of said plunger for twisting and closing the forward end of the wrapper tube and means for 15 engaging and holding the wrapper tube against rearward movement with the reciprocating plunger and against rotary movement resulting from strains imparted to the wrapper tube by said twisting means.
10. In a wrapper tube forming machine, a table, a plunger mounted for reciprocatory movement on said table, adjustable motor actuated means for imparting reciprocatory movement to said plunger, means for giving a flat strip of wrapping material tubular shape and delivering the same on to the plunger and motor driven means for engaging the forward end of the tubular wrapper to twist and close the engaged end in advance of said plunger.
11. A wrapper tube forming machine as set forth in claim 10, with means for engaging and holding the tubular wrapper against rearward movement with said plunger and against rotary movement resulting from the operation of said 35 twisting means.
12. A wrapper tube forming machine as set forth in claim 10, with means for engaging and holding the wrapper tube against rearward movement with the plunger and against rotary movement as the result of the operation of said twisting means and means in advance of said twisting means for cutting off the forward portion of the wrapper tube having the twisted and closed forward end.

VERN R. LUCE.
